DESIGN FOR A BRASSIÈRE

Lillian Hunau, Brooklyn, N. Y.

Application November 21, 1946, Serial No. 134,974

Term of patent 14 years

(Cl. D20—4)

To all whom it may concern:

Be it known that I, Lillian Hunau, a citizen of the United States, residing at Brooklyn, in the county of Kings and State of New York, have invented a new, original, and ornamental Design for Brassières, of which the following is a specification, reference being had to the accompanying drawing, forming part thereof.

In the drawing:

Fig. 1 is a perspective view of a brassière, showing my new design; and

Fig. 2 is a sectional view taken substantially along the line 2—2 of Fig. 1, and is explanatory of the openwork character of the fabric at the apices of the bust cups.

The back of the brassière is of conventional configuration.

I claim:

The ornamental design for a brassière, as shown and described.

LILLIAN HUNAU.
